UNITED STATES PATENT OFFICE.

JULIUS M. ULRICH AND WILLIAM RAHR, JR., OF MANITOWOC, WISCONSIN; SAID ULRICH ASSIGNOR TO SAID RAHR.

CARBURETER.

1,081,258.

Specification of Letters Patent.

Patented Dec. 9, 1913.

Application filed August 27, 1910. Serial No. 579,324.

To all whom it may concern:

Be it known that we, JULIUS M. ULRICH and WILLIAM RAHR, Jr., citizens of the United States, residing at Manitowoc, county of Manitowoc, and State of Wisconsin, have invented new and useful Improvements in Carbureters for Internal-Combustion Engines, of which the following is a specification.

10 Our invention relates to improvements in carbureters for internal combustion engines.

Our present invention has for its object the provision of means for producing a similar pulsating pressure upon the liquid and the initial delivery of the liquid through the nozzle in connection with means whereby only a portion of the cylinder air charge is delivered to the mixing chamber past the 20 nozzle, another portion of the air being delivered into the mixing chamber at a point above the fuel nozzle where it is mixed with the charged air or vapor.

By dividing the air current, we are enabled to use one portion of it initially to aid in spraying and distributing the liquid charge over the walls of the mixing chamber. We are also able to delay the delivery of the other portion of the air charge and thus build up an anterior pressure in the passages sufficient to produce a forcible liquid discharge at the nozzle, whereby the liquid may be thrown and distributed over the upper portion of the walls of the mixing chamber, preparatory to the delivery of such portion of the air charge to the mixing chamber. We secure a delay in the delivery of one portion of the air charge by providing a by-pass leading around that portion of the mixing chamber in which the nozzle is located, to the upper portion of such chamber, and providing a resisting member in this by-pass of such character that an air pressure may be built up in the by-pass and directed through an auxiliary duct upon the surface of the liquid supply to forcibly eject liquid from the nozzle before the pressure is sufficient to overcome the inertia and friction of the resisting member, said member, however, being adapted to move and uncover the connection between the by-pass and the mixing chamber, when a pre-determined pressure is exerted against it, whereupon a portion of air passes through 55 the by-pass, dilutes the vaporized mixture

in the mixing chamber and vaporizes the residual portion of the liquid charge.

In the following description reference is had to the accompanying drawings in which:—

Figure 1 is a vertical sectional view showing our improved carbureter, drawn to a plane common to the central portions of the mixing chamber and by pass, and also showing a portion of an engine cylinder in section on a plane extending through the inlet port of the cylinder and the connection of the mixing chamber outlet therewith. Fig. 2 is an elevation of the same as it appears when applied to a two cylinder two cycle engine.

Like parts are identified by the same reference characters throughout the several views.

In the construction shown a portion of the 71 crank chamber 1 and a portion of the compression chamber 2 of a two cycle engine are illustrated in connection with a carbureter embodying our invention. Admission and delivery of air to and from the crank 80 chamber is controlled by a rotary two way plug valve 4, which is provided with a port 6 adapted to register with and connect through the air inlet ports 8 and 10 of the crank chamber and valve casing or the air 85 outlet port 12 of said chamber and the inlet port 14 of the mixing chamber 16. The air becomes charged with hydrocarbon vapor in the upper portion of the mixing chamber 16 and is delivered to the compression chamber 90 2 of the engine through the port 18.

The liquid fuel is delivered to the mixing chamber from a chamber 20 (preferably a float chamber) through a duct 22 and nozzle 23, the flow of liquid through the latter being in part controlled by the needle valve 24. The mixing chamber is partially subdivided below the outlet of the nozzle 23 by a member 26 driven into the lower portion of the mixing chamber or otherwise secured 100 in position therein having an aperture 28 through which the nozzle 23 extends and which forms an air passage connecting the lower with the upper portion of the mixing chamber. The lower and upper portions of 105 the mixing chamber are also connected by a by-pass having a vertical portion 30 provided with a piston valve 32, which controls the delivery of air through the vertical portion of the by-pass into the outlet portion 110

thereof, which communicates with the outer portion of the mixing chamber 16. This piston valve 32 is adapted to be lifted by the pressure of air in the by-pass until the air is permitted to escape through the outlet 34 into the mixing chamber. The capacity of the aperture 28 (which is preferably circular in form) is less than the capacity of the valve port 6 and the ports 12 and 14, these ports having preferably the form of elongated slots. When these ports are open, therefore, a back pressure will be created in the lower part of the mixing chamber below the member 26 and this pressure will be exerted through the by-pass to lift the piston 32. The pressure thus developed in the by-pass is utilized to force a discharge of the liquid fuel through the duct 22 and nozzle 23 by providing a duct 36 which leads directly from the vertical portion of the by-pass into the float chamber 20, thus permitting the air pressure to be exerted upon the surface of the liquid in the said chamber. This pressure will exceed the pressure in the upper portion of the mixing chamber 16 above the member 26 and therefore cause a discharge of the liquid through the nozzle 23.

When the pressure in the by-pass becomes sufficient to overcome the inertia and friction of piston 32, the latter will be lifted to uncover the outlet 34. A considerable reduction in the pressure of the air in the by-pass will then take place, for the reason that the inertia and friction of the piston will then be exerted to prevent its downward movement and the outlet 34 is of such capacity as to permit a substantially instant equalization of pressure in the by-pass with that in the mixing chamber. It is not necessary that the equalization should be complete, but it is desirable that it should be sufficiently complete to cause a material reduction in the liquid delivery, if not an entire cessation of such delivery.

With the described construction, whereby the liquid is discharged through the nozzle with considerable force during the period of maximum pressure, the needle valve 24 may be more nearly closed than in the ordinary carburetor where the delivery of the liquid depends merely upon the slight suction exerted at the nozzle. It therefore follows that when the reduction in pressure takes place in the by-pass, no appreciable quantity of liquid will pass through the nozzle, substantially the entire liquid charge having been delivered before the resisting piston 32 can uncover the outlet or port 34. We prefer a weighted piston or plunger to an ordinary spring actuated valve, for the purpose of providing the necessary resistance to the passage of air through the by-pass, for the reason that a weighted piston or plunger is slow in its operation, both in opening and in closing when compared with the opera-

tion of a spring controlled valve of light weight. The piston 32 does not start promptly, and when in motion, it continues in motion until the outlet 34 is quite fully open. In the ordinary operation of a hydro-carbon engine, the piston will not return to cut off the outlet opening 32 until the end or nearly the end of the period of air delivery. This permits a greater degree of equalization in pressure during the open period than would be permitted by a spring actuated valve. A duct 40 communicates between the upper portion of the mixing chamber 16 and the space 42 above the piston 32. A ball valve 44 obstructs the flow of air or vapor through this duct to the mixing chamber and thus permits an air cushion to form above the piston valve 32 but allows air to enter the space above this piston valve from the mixing chamber when the valve 32 descends. We thus accomplish the double purpose of cushioning the piston valve and of permitting it to descend freely after the delivery of the air charge to the mixing chamber.

A screw threaded member 46 is adjustably mounted in the casing above the ball valve 44, whereby the movement of said ball is limited. This feature of our construction, involving the duct 40 and valve 44, is of especial importance where a throttle valve, such as valve 48, is employed to regulate the speed of the engine by controlling the delivery of vapor through the port 18. These valves are located, in accordance with ordinary practice, at the inlet to the engine cylinder, *i. e.*, the outlet of the carburetor, and in the construction illustrated they are located beyond the connection of the duct 40 with the mixing chamber. When the throttle valve 48 is partially closed, considerable pressure may be developed in the mixing chamber and by-pass 20, if air under pressure is being delivered through the inlet port 14. The by-pass, however, permits the air or vapor to pass from the mixing chamber to the space above the piston 32, thus permitting piston 32 to descend, since the pressure above valve 32 cannot fall materially below the pressure in the mixing chamber.

It will be understood that the valve 48 is an oscillatory valve operated manually. When an engine is governed in the usual manner the rotary plug valve 4 may also be actuated from the engine in any ordinary manner, the means for operating such valves being well understood and, therefore, not illustrated herein. It will also be understood that the float 50 in float chamber operates in the ordinary manner through a lever 51 and valve 52 to control the delivery of liquid to the float chamber from any suitable source of supply through the inlet duct 54.

Where a single carburetor is employed in

an engine having more than one cylinder and piston, a rotary valve 4 will be employed for each cylinder, and the inlet ports of the mixing chamber will contact with 5 passages 56 leading to the lower portion of the mixing chamber. The upper portion of the mixing chamber will be similarly connected by outwardly extending passages 58 with the cylinder ports 18. Where this is 10 done the duct 40 will preferably be connected with the passage 58 at one or both sides of the mixing chamber 16.

While we have shown and described our invention as applied to a two cycle engine, 15 we do not limit the scope of our claims to the combination with such an engine, since it is obvious that it is applicable to any form of engine where a difference is secured between the pressure in the mixing chamber 20 at the point of fuel delivery and that of the air before it reaches such point. In an ordinary two cycle engine this difference is created by compression in the crank chamber, while in a four cycle engine it is secured 25 by the partial vacuum developed in the mixing chamber during the suction stroke of the engine piston, by applying an initial air pressure to the surface of the liquid in excess of the pressure at the nozzle, and forcible delivery of the liquid fuel is thus secured, and this delivery being initial, it is obvious 30 that the delivered fuel will be exposed to all the air passing through the aperture 28 and the fuel thereby effectually vaporized. 35 The delivery of the liquid through the nozzle being a forcible delivery, produced virtually by an impact pressure of air in the float chamber, it is obvious that such liquid delivery is not materially affected by 40 relative density;—at least the delivery of such liquid will not be affected by a variation in density greater than the increase or decrease of the fuel value of the liquid due to the variation in density; it would also 45 be observed that the delivery of the liquid fuel is not dependent upon the height of the liquid in the float chamber, there being practically no difference in the quantity delivered, whether float chamber is nearly full 50 or nearly empty. We regard the use of the rotary valve 4 or its equivalent as very important for the purpose of timing the pressure impulse upon the fuel and developing a considerable degree of kinetic energy in 55 the air entering the float chamber. This enables us to virtually secure what we call a hammer pressure upon the liquid fuel which ejects it under the influence of shock. This hammer pressure is due to the in-rush of air 60 when valve 4 opens, and is similar in effect to that secured in a hydraulic ram, although the force is greatly diminished by reason of the elastic character of the fluid, which diminishes the shock. The result is, however, 65 that a quick and positive jet of liquid

fuel is delivered. This is true whether the carbureter is employed for a two cycle or for a four cycle engine, since the valve 4 may allow a vacuum to build up in all parts of the mixing chamber before opening to 70 atmospheric air, and therefore the opening of said valve provides for a sudden rush of air through the carbureter either from the atmosphere, or from a compression chamber in case the carbureter is used in connection with a two cycle engine and air under pressure delivered without reducing the pressure in the mixing chamber materially below atmospheric pressure.

Having thus described our invention what 75 we claim as new and desire to secure by Letters Patent is—

1. A carbureter for internal combustion engines comprising the combination with a mixing chamber provided with a valved air inlet, a vapor outlet and a fuel inlet at an intermediate point, of an obstruction in said chamber, located between the air and fuel inlets and adapted to direct a portion of the air to the fuel entering through the fuel inlet, a by pass leading around said obstruction, a fuel supply chamber provided with an outlet communicating with the fuel inlet of the mixing chamber, and also having an open connection between its upper portion and the by pass, and a yielding obstruction in said by pass between said open connection with the fuel chamber, and the point of air delivery to the mixing chamber beyond the obstruction therein, together with a posterior 95 throttle controlling the delivery of the mixture through the outlet.

2. A carbureter for internal combustion engines, comprising the combination with a mixing chamber provided with a valved air inlet, a vapor outlet and a fuel inlet, of a by pass connecting the inlet and outlet portions of the mixing chamber, around the portion occupied by the fuel inlet, means for restricting the passage of air through that portion of the mixing chamber occupied by the fuel inlet, a yielding obstruction to the passage of air through the by pass, and means for utilizing the air in the by pass in advance of said obstruction, to develop a pressure upon the fuel in advance of the fuel inlet, together with a posterior throttle controlling the delivery of the mixture through the outlet.

3. A carbureter for internal combustion engines, comprising the combination with a mixing chamber provided with a valved air inlet, a vapor outlet and a fuel inlet, of a by pass connecting the inlet and outlet portions of the mixing chamber, around the portion occupied by the fuel inlet, means for restricting the passage of air through that portion of the mixing chamber occupied by the fuel inlet, a yielding obstruction to the passage of air through the by pass and 130

- means for utilizing the air in the by pass in advance of said obstruction, to develop a pressure upon the fuel in advance of the fuel inlet, said means comprising a fuel chamber 5 having its lower portion in communication with the fuel inlet and its upper portion in communication with said by pass, together with a posterior throttle controlling the delivery of the mixture through the outlet.
- 10 4. A carbureter for internal combustion engines, comprising the combination with a mixing chamber provided with a valved air inlet, a vapor outlet and a fuel inlet, of a by pass connecting the inlet and outlet portions of the mixing chamber, around the portion occupied by the fuel inlet, means for restricting the passage of air through that portion of the mixing chamber occupied by the fuel inlet, a yielding obstruction 15 to the passage of air through the by pass and means for utilizing the air in the by pass in advance of said obstruction, to develop a pressure upon the fuel in advance of the fuel inlet, said means comprising a fuel chamber having its lower portion in communication with the fuel inlet and its upper portion in communication with said by pass, and said yielding obstruction comprising an automatically closing valve, located in the by pass and adapted to be actuated to open 20 position by the pressure of air thereon, together with a posterior throttle controlling the delivery of the mixture through the outlet.
- 25 5. A carbureter for internal combustion engines, comprising the combination with a fuel supply chamber, a mixing chamber provided with a valved air inlet, a vapor outlet, and an intermediate fuel inlet of a by pass connecting the air inlet and the outlet portions of said chamber around the portion occupied by the fuel inlet, means for restricting the passage of air past the fuel inlet, an automatically closing valve in the by pass, 30 a duct connecting the by pass in advance of said valve with the upper portion of the fuel chamber, and a duct connecting the lower portion of the fuel chamber with the fuel inlet, said valve being adapted to open under 35 a predetermined pressure in the by pass, together with a posterior throttle controlling the delivery of the mixture through the outlet.
- 35 6. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 40 a duct connecting the by pass in advance of said valve with the upper portion of the fuel chamber, and a duct connecting the lower portion of the fuel chamber with the fuel inlet, said valve being adapted to open under 45 a predetermined pressure in the by pass, together with a posterior throttle controlling the delivery of the mixture through the outlet.
- 45 7. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 50 a duct connecting the by pass in advance of said valve with the upper portion of the fuel chamber, and a duct connecting the lower portion of the fuel chamber with the fuel inlet, said valve being adapted to open under 55 a predetermined pressure in the by pass, together with a posterior throttle controlling the delivery of the mixture through the outlet.
- 55 8. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 60 a duct connecting the by pass in advance of said valve with the upper portion of the fuel chamber and a duct connecting the lower portion of the fuel chamber with the fuel inlet, said valve being adapted to open under a predetermined pressure in the by pass and having the space back of the valve connected 65 by an auxiliary duct with the mixing chamber.
- 65 9. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 70 a duct connecting the by pass in advance of said valve with the upper portion of the fuel chamber and a duct connecting the lower portion of the fuel chamber with the fuel inlet, said valve being adapted to open under a predetermined pressure in the by pass and having the space back of the valve connected by an auxiliary duct with the mixing chamber.
- 75 10. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 80 a duct connecting the by pass in advance of said valve with the upper portion of the fuel chamber and a duct connecting the lower portion of the fuel chamber with the fuel inlet, said valve comprising a piston valve provided with an auxiliary valved passage communicating between the mixing chamber and the space back of the piston valve, to admit air to such space sufficiently to permit the valve to close after it has been opened by the pressure in the receiving portion of the by pass.
- 85 11. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 90 a duct connecting the by pass in advance of said valve with the upper portion of the fuel chamber and a duct connecting the lower portion of the fuel chamber with the fuel inlet, said valve comprising a piston valve provided with an auxiliary valved passage communicating between the mixing chamber and the space back of the piston valve, to admit air to such space sufficiently to permit the valve to close after it has been opened by the pressure in the receiving portion of the by pass.
- 95 12. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 100 a duct connecting the by pass in advance of said valve with the upper portion of the fuel chamber and a duct connecting the lower portion of the fuel chamber with the fuel inlet, said valve being adapted to open under a predetermined pressure in the by pass, together with a posterior throttle controlling the delivery of the mixture through the outlet.
- 105 13. A carbureter for internal combustion engines, comprising the combination with a fuel supply chamber, a mixing chamber provided with a valved air inlet, a vapor outlet, and an intermediate fuel inlet, of a by pass connecting the air inlet and the outlet portions of said chamber around the portion occupied by the fuel inlet, means for restricting the passage of air past the fuel inlet, an automatically closing valve in the by pass, 110 a duct connecting the by pass in advance of said valve with the upper portion of the fuel chamber and a duct connecting the lower portion of the fuel chamber with the fuel inlet, said valve being adapted to open under a predetermined pressure in the by pass, together with a posterior throttle controlling the delivery of the mixture through the outlet.

In testimony whereof we affix our signatures in the presence of two witnesses.
